MOBILE BODY

Abraham Wolf, Vineland, N. J.

Application January 16, 1946; Serial No. 641,524

2 Claims. (Cl. 170—159)

1

This invention relates to mobile bodies adapted to travel through fluid media, such as aircraft, marine vessels and the like, and more particularly to improved propeller structure therefor.

It is well known that a part of the resistance offered to the forward movement of aircraft employing propellers is due to the compacted body of air which is built up in the region immediately in front of the hub and inner ends of the blades of the propeller which radiate from the hub. In the vicinity of this region, the propeller has very little, if any, propelling power. This is due to the fact that the air in this region is not driven rearwardly by the rotating propeller, as is the air at a greater radial distance outwardly from the hub where the blades act upon the air to impart rearward motion thereto. In general, the same is also true of propeller driven marine vessels, the propellers of which encounter similar resistance by the water. Many attempts have been made heretofore to eliminate, or at least to materially reduce, this compacted body of fluid medium in front of the hub and the region therearound, but these have met with little success, so far as I am aware.

The primary object of my invention is to provide, in aircraft, marine vessels, and similar mobile bodies which are designed to travel through fluid media, an improved propeller construction which will very greatly reduce the aforementioned, compacted, fluid body, and therefore will greatly increase the efficiency of such mobile bodies.

More particularly, it is an object of my invention to provide an improved attachment for propellers of mobile bodies of the type set forth above which will be effective to increase the bite of the propeller blades in the fluid medium in which it operates to thereby increase the speed of the moving body for a given power consumption, or, for a given speed, will require less power.

Another object of my invention is to provide an improved attachment for propellers as aforesaid which can be applied readily to most existing propellers.

Still another object of my invention is to provide an improved propeller structure for aircraft which will tend to lessen the effect of head winds by "drilling" through the air, so to speak.

A further object of my invention is to provide an improved propeller construction for aircraft and the like which will tend to minimize drifting, off course flying, and sudden drops of the craft.

Still a further object of my invention is to provide an improved propeller construction as set

2

forth above which will tend to reduce vibration of the rotating parts to a minimum, thereby helping to increase the life of the driving motor therefor.

It is also an object of my invention to provide an improved attachment for propellers as set forth above which is very simple in construction, economical in cost, and highly efficient in use.

In accordance with my invention, I provide, as 10 an attachment to the propeller on the front thereof and for rotation therewith, a substantially conical member constructed to "bore" through the fluid medium, as it were, and thereby overcome the compacted body normally existing 15 in the fluid medium in front of the propeller hub region. For this purpose, the conical nose-piece is provided with a plurality of helical grooves or channels in its surface extending from its forward, apex end all the way back to its base end 20 against which the propeller blades are disposed. Each groove terminates at the rear surface of one of the propeller blades and receives and guides a stream of the fluid medium tangentially onto its associated blade. This breaks up the compacted 25 fluid body and provides fluid at the normally inactive region of the propeller for the blades to bite into. Preferably, the base diameter and length of the conical nose-piece is of the order of one-third the diameter of the circle described 30 by the outer ends or tips of the propeller blades as the propeller rotates. A similar nose-piece structure may be employed to advantage in shells or other similar explosive projectiles which are projected through air or water.

The novel features that I consider characteristic of my invention are set forth with particularity in the appended claims. The invention itself, however, both as to its organization and method of operation, as well as additional objects and advantages thereof, will best be understood from the following description, when read in connection with the accompanying drawing in which

Figure 1 is a front elevation of an aeroplane propeller provided with a nose-piece attachment in accordance with my invention;

Figure 2 is a top plan view thereof;

Figure 3 is a rear elevation thereof;

Figure 4 is an elevation of the nose-piece of Figures 1-3 as seen from the base end thereof;

Figure 5 is a view partly in section of the stern of a ship having a propeller structure in accordance with my invention;

Figure 6 is an enlarged, top plan view of the propeller structure of Figure 5, and

Figure 7 is a fragmentary side elevation of an

explosive shell having a nose formed in accordance with my invention.

Referring more particularly to the drawing, wherein similar reference characters designate corresponding parts throughout, there is shown, in Figures 1-3, an aeroplane propeller having a hub 1 which is adapted to be secured to a propeller shaft and from which radiate three suitably pitched blades 2 in known manner. Secured to the front of the propeller, as by screws 3, is a substantially conical nose-piece 4 the base or larger end of which is disposed against the blades and the body of which extends forwardly of the propeller so that the apex end thereof is in advance of the propeller in the direction of movement of the aeroplane of which the propeller is a part. Preferably, the base end of the nose-piece 4 is formed with a central seat 5 for the reception of the hub 1 and with a plurality of radial slots 6 which extend outwardly from the central seat 5 each for the reception of one of the blades 2. The propeller is thus set into the base of the nose-piece 4 somewhat as best seen in Figure 2.

The nose-piece 4 is formed in its conical surface with a plurality of helical grooves or channels 7 which extend from the apex end to the base end thereof, there being as many grooves 7 as there are blades 2, and each groove 7 being associated with a different blade. Preferably, although not necessarily, each groove 7 is of less than a complete or full turn, as best seen in Figure 1, and preferably, also, each groove widens gradually from the apex end to the base end of the nose-piece, each groove 7 merging into its associated blade 2 at the rear surface thereof, as best seen at the center blade 2 in Figure 2.

The nose-piece 4 may be made of any suitable, non-corrosive, light weight material so that it will not add any appreciable weight to the aeroplane. As the propeller and nose-piece rotate as a unit during flight, the nose-piece "bores" into the air and each of the grooves 7 receives and guides to the rear surface of its associated blade 2 a stream of air. The several air streams are directed tangentially onto the rear surfaces of their respective blades by reason of the fact that each groove 7 merges thereinto as described above. In this way, the normally compacted body of air in front of the hub 1 and the inner portions of the blades 2 is broken up and fed to the blades which are then enabled to improve their bite in the air, since these inner portions of the blades are normally quite ineffective. I have found that, for optimum results, the base diameter and length of the nose-piece 4 should preferably be about equal and that each should preferably be of the order of one-third of the diameter of the circle described by the outer ends of the blades 2. However, these proportions may be varied to a considerable extent depending upon the size and pitch of the blades, the depth and width of the grooves 7, and so on.

In Figure 5, I have shown my invention applied to a ship 8 having a propeller shaft 9 to which the propeller represented by the blades 10 is secured. Here, the nose-piece 4 has an axial bore through which the shaft 9 passes and the nose-piece is also secured to the shaft 9, the base end of the nose-piece being formed with radial seats for reception of the blades 10 in a manner similar to that described above. The apex end of the nose-piece faces the stern of the ship and the helical grooves 7 therein extend back to the base end where each merges into the rear surface of its associated blade 10.

As the propeller 10 and its nose-piece 4 rotate, the grooves 7 direct streams of water tangentially onto the normally ineffective, inner, rear surface regions of the blades 10, thereby increasing the bite of the blades 10 in the water and improving the efficiency. This construction is especially suited for electrically powered and turbine equipped ships because of the smoothness of its water bite.

In Figure 7 I have shown an explosive shell 11 provided with a nose 12 which is formed with a plurality of helical grooves in accordance with my invention. The nose 12 may be of conventional ogival shape and the helical grooves 7 therein extend from the tip or apex end of the nose to the large end thereof, each being preferably about an eighth of a turn and substantially merging into the shell casing at the large end of the nose. When a conventional shell is fired from a cannon, for example, air pressure is built up at the nose of the shell and this retards the flight of the shell more or less. However, when a shell constructed in accordance with my invention is fired, the helical grooves 7 therein, which are turned in the same direction as the direction of rifling, enable the shell to "drill" through the air and thereby overcome the air resistance. Hence, my improved shell will travel faster and will have a more powerful impact when it strikes a target. Moreover, a shell constructed as above described is less subject to wind drift and therefore can be fired with greater accuracy.

Although I have shown and described several forms of my invention, it will undoubtedly be apparent to those skilled in the art that many other forms thereof, as well as variations in those described, are possible within the spirit of my invention. I therefore do not wish to be limited except insofar as is made necessary by the prior art and by the spirit of the appended claims.

I claim as my invention:

1. In a vehicle adapted to move through a fluid medium and including a rotary propeller for propelling said vehicle through said medium, a nose-piece comprising a substantially conical member mounted in advance of said propeller on an axis coincident with the axis of rotation of said propeller, said member being rotatable with said propeller and having a plurality of circumferentially distributed, helical grooves in the surface thereof each extending from its apex end to its base end, the number of said grooves being equal to the number of blades in said propeller, each of said grooves being associated with and terminating at the rear face of a separate one of said blades, said grooves being adapted to receive and guide therealong to the rear of said blades streams of said medium as said propeller rotates to advance said vehicle through said medium, the base end of said nose-piece being provided with a plurality of seats, one for each of said blades, said nose-piece being disposed against said propeller with the blades thereof received in said seats, and the base end of each of said grooves being positioned to direct tangentially onto the rear surface of the blade associated therewith the stream of said medium guided thereby.

2. In a vehicle adapted to move through a fluid medium and including a rotary propeller for propelling said vehicle through said medium, said propeller including a hub and a plurality of blades radiating outwardly from said hub, a

nose-piece comprising a substantially conical member the base end of which is provided with a central seat for said hub and a plurality of blade seats extending radially outwardly from said central seat, said nose-piece being mounted in advance of and against said propeller on an axis coincident with the axis of rotation of said propeller and with said hub disposed in said central seat and a blade in each of said blade seats, said member being rotatable with said propeller and having a plurality of circumferentially distributed, helical grooves in the surface thereof each extending from its apex end to its base end, the number of said grooves being equal in number to the number of said blades in said propeller, each of said grooves being associated with and terminating at the rear face of a separate one of said blades, said grooves being adapted to receive and to guide therealong to the rear of

5 said blades streams of said medium as said propeller rotates to advance said vehicle through said medium, the base end of each of said grooves being so positioned as to direct tangentially onto the rear surface of the blade associated therewith the stream of said medium guided thereby.
